DESIGN FOR A BOTTLE OR SIMILAR ARTICLE

Joseph S. Stein, Highland Park, Ill., assignor to Lucien Lelong, Inc., Chicago, Ill., a corporation of Illinois

Application May 1, 1933. Serial No. 47,953

Term of patent 7 years

To all whom it may concern:

Be it known that I, JOSEPH S. STEIN, a citizen of the United States, and a resident of the city of Highland Park, county of Lake, and State of Illinois, have invented a new, original, and ornamental Design for a Bottle or Similar Article, of which the following is a specification, reference being had to the accompanying drawing forming a part thereof.

In the drawing:

Figure 1 illustrates a front elevational view of the bottle or similar article, embodying my invention.

Figure 2 is a top plan view thereof.

I claim:

The ornamental design for a bottle or a similar article, as shown.
